[57] CLAIM

The ornamental design for an eyeglass retainer, as
shown and described.

DESCRIPTION

FIG. 1 is a front elevational view of the eyeglass re-
tainer showing our new design;

FIG. 2 is a rear elevational view thereof;

FIG. 3 is a side elevational view thereof, the opposite
side being a mirror image;

FIG. 4 is an end elevational view thereof, the opposite
end being identical;

FIG. 5 is a reduced perspective view thereof, with a
pair of eyeglasses being shown in broken lines for illus-
trative purposes only.
